US00D625732S

(12) **United States Design Patent**
Fitzmaurice et al.

(10) **Patent No.:** **US D625,732 S**
(45) **Date of Patent:** **** Oct. 19, 2010**

(54) **USER INTERFACE FOR A COMPUTER SCREEN**

(75) Inventors: **George Fitzmaurice**, Ontario (CA); **Gord Kurtenbach**, Ontario (CA); **Justin Matejka**, Ontario (CA); **Marsha Leverock**, Ontario (CA); **Paul D. Vaters**, Ontario (CA)

(73) Assignee: **Autodesk, Inc.**, San Rafael, CA (US)

(**) Term: **14 Years**

(21) Appl. No.: **29/309,690**

(22) Filed: **Sep. 26, 2008**

Related U.S. Application Data

(63) Continuation-in-part of application No. 12/200,373, filed on Aug. 28, 2008.

(51) **LOC (9) Cl.** **14-04**

(52) **U.S. Cl.** **D14/486**
